ATTORNEY

UNITED STATES PATENT OFFICE.

HENRY E. LEIBE, OF NEWARK, NEW JERSEY.

FOLDING EYEGLASSES.

1,152,521.

Specification of Letters Patent. Patented Sept. 7, 1915.

Application filed August 29, 1914. Serial No. 859,155.

To all whom it may concern:

Be it known that I, HENRY E. LEIBE, a citizen of the United States, residing in the city of Newark, in the county of Essex and State of New Jersey, have invented certain new and useful Improvements in Folding Eyeglasses, of which the following is a full, clear, and exact description, such as will enable others skilled in the art to which it pertains to make, construct, and use the same, reference being had to the accompanying drawings, and to numerals of reference marked thereon, forming a part of this specification.

This invention relates to improvements in folding eye-glasses, and has for its object, to provide the lens frames thereof with casings curving outwardly from said lens frames and projecting toward each other, said casings having pivotally secured thereto spring-actuated nose guards, and a spring-actuated bridge so arranged that the lens frames may be folded one upon the other.

Further objects of the invention are to simplify the general construction and operation of the device, and to cheapen the cost thereof.

The construction and operation of my device will be more fully described in the specification which follows, and in the accompanying drawings, which form a part thereof, wherein I have shown a preferred embodiment of my device.

Throughout the specification and drawings, similar numerals of reference indicate like parts.

In the drawings, Figure 1 represents a front elevation of my improved device. Fig. 2 represents a plan view of the same. Fig. 3 represents a similar view, illustrating the device in folded position. Fig. 4 represents a rear view of my improved device. Fig. 5 represents an enlarged and detached view of the bridge; and Fig. 6 represents a transverse section taken on line $x-x$ of Fig. 2.

Referring to the drawings, 1 represents the frames for holding the lens and 2 the lenses, which may be of any desired form or configuration.

3 represent chambered casings or bridge-securing means carrying the nose guards and which are secured to the lens frames in any convenient manner, preferably by solder, curving outwardly from the lens frames and projecting toward each other.

A spring-actuated bridge 4 provided with tubular ends 5, is pivotally connected to the casings 3, 3 at the ends thereof by means of split-pins 6, and so arranged that the lens frames 1 carrying the casings 3, to which are pivotally secured the spring-actuated nose guards 7, may be folded one upon the other, as clearly indicated in Fig. 3 of the drawings.

A handle 8 on one end of the lens frame is provided with a guide-way, to receive the other lens frame, and is further provided with a spring-catch 9 for engagement with the entering lens frame, to lock the lens frames in folded position.

The chambered casing 3 is preferably channel-shaped in cross-section, (see Fig. 6), between the walls of which a tubular post 10 is rotatively located, the lower end of which is slotted as at 11 to receive the flattened end portion 12 of the nose guard 7. A split-pin 13 is rigidly secured in the walls of the casing and passes through a suitable aperture in the end portion 12 of the nose guard, and through the tubular post 10, by means of which the parts are held in position. A spiral spring 14 is located within the post 10 and surrounds the pin 13, one end of said spring being secured in the slot 15 of the pin and the other end is located in the slotted portion 11 of the post 10. Similar pins 6 secured to the outer ends of the casings 3 and passing through the tubular ends 5 of the bridge 4, have one end of a spiral spring 15 secured thereto in the same manner, the other end of which is secured to the tubular ends 5 in any desired manner.

Suitable stops 16 preferably formed integral with the upper portion of the bridge 4 and in close proximity to the tubular ends 5 are provided to properly position the parts when in folded position, as clearly indicated in Fig. 3 of the drawings.

The chambered casings or bridge securing means are further provided with an elongated slot 17, to receive the flattened end portion 12 of the nose guard 7.

Experience has demonstrated that the organization above described is a highly efficient one, and while the device described is the preferred embodiment of my invention, I do not wish to be limited to the exact details of construction and combination herein set forth, as minor variations thereof not involving the exercise of invention, may be made by any skilled mechanic, and such de-

partures from what is herein described and claimed, not involving invention, I consider within the scope and terms of my claims.

I claim:

- 5 1. A pair of eye-glasses comprising lenses, frames for holding the lenses, bridge-securing means on said lens frames, spring-actuated nose guards pivotally secured to said bridge-securing means, a spring-actuated 10 bridge pivotally connected to the ends of said bridge-securing means and so arranged that the lens frames may be folded one upon the other, a handle on one of the lens frames and locking means on the handle for engagement with the other lens frame to lock the lens frames in folded position.
- 15 2. A pair of eye-glasses comprising lenses, frames for holding the lenses, bridge-securing means on said lens frames projecting toward each other, each of said bridge-securing means being provided with a slot, 20 spring-actuated nose guards provided with flattened end portions pivotally secured to said bridge-securing means, said flattened 25 end portions projecting through the slots in said bridge-securing means, a spring-actuated bridge provided with stops, pivotally connected to the ends of the said bridge-securing means and so arranged that the lens 30 frames may be properly positioned and folded one upon the other.
3. A pair of eye-glasses comprising lenses, frames for holding the lenses, bridge-securing means on said lens frames projecting 35 toward each other, each of said bridge-securing means being provided with a slot, spring-actuated nose guards provided with flattened end portions pivotally secured to said bridge-securing means, said flattened 40 end portions projecting through the slots in said bridge-securing means, a spring-actuated bridge provided with stops, pivotally connected to the ends of the said bridge-securing means and so arranged that the lens 45 frames may be properly positioned and folded one upon the other, a handle on one

of the lens frames and locking means on the handle for engagement with the other lens frame to lock the lens frames in folded position.

4. A pair of eye-glasses comprising lenses, frames for holding the lenses, slotted channel-shaped bridge-securing means on said lens frames projecting toward each other, spring-actuated nose guards provided with 55 flattened end portions pivotally secured to said bridge securing means, said flattened end portions projecting through the slotted bridge-securing means, a spring-actuated bridge provided with tubular ends, and stops 60 formed integral with the upper portion of the bridge in close proximity to the tubular ends pivotally connected to the ends of said bridge-securing means and so arranged that the lens frames may be properly positioned 65 and folded one upon the other.

5. A pair of eye-glasses comprising lenses, frames for holding the lenses, channel-shaped bridge-securing means on said lens frames projecting toward each other, a post 70 rotatively located in each of said bridge-securing means, the lower end of said post being provided with a slot, spring-actuated nose guards provided with flattened end portions pivotally secured to said bridge-securing means, said flattened end portions projecting through the slots in said bridge-securing means and said tubular posts, a spring-actuated bridge provided with tubular ends and stops formed integral 75 with the upper portion of the bridge in close proximity to the tubular ends pivotally connected to the ends of said bridge-securing means and so arranged that the lens frames may be properly positioned and folded one 80 upon the other.

This specification signed and witnessed this 13th day of July, 1914.

HENRY E. LEIBE.
